Egbert & Green,
Washing Machine.
No. 9258.

Patented Sep. 14, 1852.

UNITED STATES PATENT OFFICE.

S. L. EGBERT AND S. W. GREEN, OF WILLOUGHBY, OHIO.

CONNECTING-JOINT FOR WASHING-MACHINES OR OTHER PURPOSES.

Specification of Letters Patent No. 9,258, dated September 14, 1852.

To all whom it may concern:

Be it known that we, S. L. EGBERT and S. W. GREEN, of Willoughby, in the county of Lake and State of Ohio, have invented a new and Improved Mode of Constructing Washing-Machines; and we do hereby declare that the following is a full, clear, and exact description of the construction and operation of the same, reference being had 5 to the annexed drawings, and to the letters of reference marked thereon, making part of this specification, corresponding letters referring to like parts in the different views of the machine.

10 To enable others skilled in the art to make and use our invention we will proceed to describe its construction and operation.

Figure 1 is a perspective view; Fig. 2, a transverse section. The other views will be 20 referred to in the further description of our invention.

We construct the box A Figs. 1 and 2 about 26 in. long from B to C Fig. 1, and 24 in. wide at the top from D to E Figs. 1 25 and 2 and decreasing gradually to 18 in. at the bottom from F to G Fig. 1. This tub or box is placed on the frame H Fig. 1 in such a manner that it can be easily taken off and replaced at pleasure. At the top of the 30 box A is placed the shaft I which revolves in boxes at each end. The gear J and crank K forms the outside shoulders of the shaft's journals. The cog wheel J is placed in gear with the pinion L which is attached to the 35 crank shaft M. The motion is conveyed to the beater N Fig. 2 by means of the adjustable connecting rod O Figs. 2 and 3 which is attached to the crank shaft M by means of the crank and the other end of the lower 40 section of the connecting rod is attached to the stationary spring board P by the joint Q Figs. 2 and 3. This joint has a backing piece R Figs. 3, 4 and 5 to prevent the end of the connecting rod from wearing away the 45 spring board, it also prevents any backlash- 50 ing or noise and secures at the same time an easy vibrating motion.

Fig. 5 is a section of Fig. 4, in the direction of the lines marked $\alpha\alpha$.

50 The strap S Figs. 2 and 3 acts as a bearing for the joint and also secures the rod in place on the spring board. By our adjustable connecting rod O Figs. 2 and 3 and

stationary spring board P Fig. 2 we gain very important advantages, first our connecting rod being composed of two parts the lower containing teeth as seen at T Figs. 3 and 4, one end of the upper section forms a finger which is slipped into any of the teeth T and retained by means of the bolt and thumb screws, there is a slot in the lower section of the rod corresponding to the slot U Fig. 4 through which passes the bolt and which allows the extension and contraction of the rod as the nature of the case may require in washing. There is also a gain in the lower piece of the rod corresponding to V Fig. 4 for the feather W Fig. 3, this has the great advantage of strengthening and keeping the rod in a straight line.

70 The advantage of a stationary spring board is evident from the fact that when ever they are adjustable they soon become loose and speckling by the action of steam and water, and by the vibrating motion of 75 the beater a backlash is given to the adjustable spring board but this difficulty is entirely removed by the application of our stationary spring board P Fig. 2, as it is secured to the arms τ Figs. 1 and 2 of the 80 beater it cannot become loose and we obtain additional advantages by the introduction of the adjustable connecting rod without any of the aforesaid evils because the rod is easily adjusted to the quantity of clothes 85 in the box working securely without noise.

We consider that placing the crank and shaft M on the outside of the box or tub A a decided improvement from the fact that it is more convenient and is protected from the 90 action of steam and water and the friction is much reduced by revolving in composition boxes.

The projection X which is attached to the back part of the beater confines and prevents the water from being thrown out or spattering during the process of washing by the back action of the beater the water is thrown against the inclined back board Y which causes the water to be deflected 100 against the projection Z. The fly wheel w Figs. 1 and 2, is to give steady motion to the machine.

105 It is proper to state that the depression X' in connection with the projection X forms a recess for the water in the back-

ward movement of the beater thereby facilitating the passage of the water under it.

What we claim as our invention and desire to secure by Letters Patent is—

5 The construction of the joint (by which the connecting rod is attached to the spring board) by means of the knife edges disposed in a right line and confined by the

straps and backing pieces substantially as herein set forth.

S. L. EGBERT.
S. W. GREEN.
